HOLLOW BACK SHOVEL

Filed Sept. 25, 1922

UNITED STATES PATENT OFFICE

MARTIN HOKANSON, OF DULUTH, MINNESOTA, ASSIGNOR TO MARSHALL-WELLS COMPANY, OF DULUTH, MINNESOTA, A CORPORATION OF NEW JERSEY

HOLLOW-BACK SHOVEL

Application filed September 25, 1922. Serial No. 590,382.

The object of my invention is to provide a shovel in which the handle reinforcing strip will have its maximum strength and weight at the point where the shovel is subjected to 5 the greatest strain, and its minimum weight and strength at the point where there is comparatively little strain on the handle when in use; in other words, a shovel so constructed that the maximum stress of the metal reinforcement in any section of the handle is 10 practically proportional to the strains acting in the same section, thereby providing a stronger and better implement and effecting a considerable economy in the use of metal 15 in the reinforcing strip, as well as making it lighter in weight.

A further object is to provide a metal reinforcement which will make it possible to provide a continuous smooth cylindrical surface at the point where the workman's hand slides on the shovel handle.

A further object is to provide an improved construction of grip which can be easily and quickly fitted to the end of the handle and will present a neat, substantial appearance to the end of the shovel, combined with maximum and minimum weight.

Other objects of the invention will appear from the following detailed description.

The invention consists generally in various constructions and combinations all as hereinafter described and pointed out in the claims.

In the accompanying drawings forming part of this specification,

Figure 1 is a front view of a shovel in which the socket on the blade is shown on the top of the shovel.

Figure 2 is a longitudinal sectional view of the same showing the position of the socket at the front of the blade.

Figure 3 is a view of the rear of the blade showing its smooth unbroken surface.

In the drawing, 2 represents the blade of the shovel having the usual hollow back construction as indicated at 3, the end of the blade being folded to form a socket 4^a to receive the end of the handle. This handle is preferably made of wooden sections 5 recessed at 6 so 50 that the surface of the socket will be flush

with the surface of the handle when the parts are assembled, the end of the handle projecting down into the hollow back as usual in shovel construction.

A reinforcing plate or strip 7, preferably of steel, is interposed between the sections 5 of the handle, and extends from end to end thereof. This steel plate is preferably rolled so that it assumes a tapered form gradually decreasing in thickness toward the grip end of the handle with its point of maximum thickness and strength where the wooden handle sections enter the socket of the blade, for at this point the shovel is subjected to the greatest strain when in use. At the upper end of the handle, or adjacent the grip, the reinforcing plate may be comparatively thin, for at this point the handle is subjected to its minimum load or strain. By providing this taper in the plate, I am able to effect a considerable saving in metal and in the weight of the shovel, and at the same time provide a wide margin of safety at the point where breakage in the shovel handle usually occurs.

I am also able to reduce the size of the wood sections at the point where the workman grips the handle providing here a continuous, smooth, cylindrical surface which can be easily gripped and will not in any way injure the workman's hands. The handle sections and the reinforcing plate are secured together by suitable means, such as rivets 8 which pass through the sections and the reinforcement and also through the walls of the socket into which the wooden handle sections are inserted. The heads of these rivets are countersunk or imbedded in the metal walls of the socket, and in the wooden sections have suitable washers on the ends of the rivets, thus eliminating all rough projecting surfaces on which the hands of the workman might catch.

At the outer end of the handle, I provide the supporting means for the grip proper, consisting of arms 9 stamped from sheet metal and extending outwardly from a sleeve or collar 10, pressed from sheet metal with the arms, and split longitudinally to fit the reduced end 11 of the handle secured thereto, and to the reinforcement plate by a suitable

100

rivet as described. The arms 9 preferably have a longitudinal rib 10^a formed therein which serves to brace and stiffen them, and at the outer ends of the arms, cups 13 are formed adapted to receive the ends of a wooden grip 14 that is curved slightly and is secured to said cups by a rivet 15 passing lengthwise therethrough and eccentrically to prevent turning of the grip in the handle.

10 In Figure 1, the socket 4^a is shown on the front of the shovel blade instead of at the rear. When the shovel is made in this way, the rear surface of the blade will be smooth and unbroken as shown in Figures 2 and 3.
15 The edge 4^b of the blade is turned forward or upward to provide a rest for the foot of the user.

20 I do not wish in this application to confine myself to any particular size or thickness of the steel reinforcing plate or the degree of taper thereof; the essential feature being the idea of providing a maximum amount of metal in the reinforce at the point in the shovel handle where the strength is most needed, and reducing the metal in the reinforcing plate to a minimum at the point where great strength is not necessary.

25 I claim as my invention:

30 1. A shovel, scoop or spade comprising a blade turned forwardly at its upper end to form a foot rest and having an extension at said end folded forwardly to form a tubular handle receiving socket the meeting edges of the tubular socket being in front of the 35 blade, a handle composed of separable sections having their lower ends fitting into said socket with the ends of the sections resting against the front of the blade, a handle grip having a sleeve to receive the other end of said handle, and a metallic reinforcing plate inserted between the handle sections and extending into said socket and said sleeve and secured therein.

40 2. A shovel, scoop or spade comprising a blade having a smooth unbroken back surface and turned forwardly at its upper end to form a foot rest, a sheet metal extension of said blade and foot rest centrally arranged thereof and having upwardly extending longitudinal edges folded forwardly to form a tubular handle receiving socket, a handle comprising a metallic blade extending from end to end thereof, wooden sections on either side of the blade in the socket, the blade and sections terminating at their lower end on the interior front of the shovel, a hand grip having a sleeve to receive the upper ends of said sections and blade, and means to secure the sections and blade within said socket and sleeve.

45 In witness whereof, I have hereunto set my hand this 18th day of September, 1922.

MARTIN HOKANSON.
